UNITED STATES PATENT OFFICE.

HORACE C. HEON, OF CHICAGO, ILLINOIS, ASSIGNOR TO AUTOMOTIVE MAINTENANCE MACHINERY CO., OF CHICAGO, ILLINOIS, A CORPORATION OF ILLINOIS.

DRESSING TOOL FOR ABRADING STONES.

Application filed May 18, 1925. Serial No. 30,943.

To all whom it may concern:

Be it known that I, HORACE C. HEON, a subject of the King of Great Britain, residing at Chicago, in the county of Cook and State of Illinois, have invented certain new and useful Improvements in Dressing Tools for Abrading Stones, of which the following is a specification.

My invention relates to means for dressing the active surfaces of abrading stones, and more particularly to a hand tool for dressing the abrasive elements of cylinder-grinding tools. Cylinder-grinders are known, and in general commercial use, wherein a plurality of relatively long and slender abrading elements or "stones" are respectively mounted in carrier-members which are so associated with the rotatable body member that, in operation, the several stones will act equally upon and grind the inner surface of an engine cylinder or the like; and the efficacy of such a grinding tool, for protracted use, depends largely on keeping the several stones properly dressed at their working surfaces, in order that all of said stones may protrude equally from their carriers and that each of said surfaces may be true, straight and non-tapering in shape and may present a clean, "sharp", abrading condition.

Among the objects of my invention are, to provide a hand tool for the stated dressing of the abrading elements of such a cylinder grinder, which will be simple in construction, rapid and accurate in its operation even in inexpert hands, easy to adjust and operate, and inexpensive to maintain in good operative condition. And to attain these and further objects, which will become apparent to those skilled in the art from the following description taken with the accompanying drawings, my invention consists in the combination of parts and features of construction hereinafter described and claimed.

In the drawings, Figure 1 is a side elevation of a portion of a cylinder grinder equipped with an abrading element such as the dressing-tool is to sharpen and true up; Fig. 2 is a side elevation of the dressing-tool in working position with respect to the abrading stone and the carrier for the latter; Fig. 3 is a cross-section on line 3—3 of Fig. 2; Fig. 4 is a perspective detail of an element of the dressing member shown in Fig. 3; Fig. 5 is a perspective detail of

the adjustable bearing block or carrier member for said dressing element; Fig. 6 is an edge elevation of the dressing-tool, from its working edge; Fig. 7 is a central longitudinal section on line 7—7 of Fig. 6; Fig. 8 is a side elevation of a fragment of a modified construction; and Fig. 9 is an edge elevation, from the working edge, of the structure shown in Fig. 8.

In the drawings *a* indicates a relatively long, slender abrading stone, of carbide or other suitable material, usually of approximately square cross-section, the outwardly presented portion *a'* whereof is the working surface or abrading face and the inner portion of which is invested, at the bottom and sides, in a channel-shaped sheet-metal holder *b*, reinforcing and protecting the part of the stone which it embraces. Each such stone and its holder is mounted in a carrier member *c* of which a plurality are provided, these being suitably mounted on a rotatable body *d* so that when the body is rotated the several stones may work against the inner surface of a gas engine cylinder or the like. In the particular construction typically shown the stone-carrier *c* is pivoted as at *e* to the tool body and is pressed outwardly by a spring *f*. In order to be best conditioned for grinding a true cylindrical surface each stone *a* should be dressed, at its outer or working-surface *a'* so that said surface will have its edges longitudinally parallel to the longitudinally straight, outwardly presented surfaces *c'* and *c''* of the carrier *c*, and also the crystalline structure of the working surface *a'* of the stone should be "sharp" and not loaded with previously-collected metal. Also the surface *a* should have its working face dressed to stand either at right angle or oblique angle to the side faces of the stone in such degree as will best fit the working face of the stone to the inner surface of the cylinder to be ground, according to the diameter of the cylinder and the consequent pivotal throw of the stone-carriers *c*.

The dressing-tool shown in Figs. 2 to 7 inclusive provides a body 10 which, in best practice, is considerably longer than the abrading stone to be dressed and the carrier *c* therefor, being preferably about twice as long as the stone-equipped carrier, and is of width, at its working edge, substantially wider than is the stone to be dressed,

so as to afford guide-surfaces 11 and 12 which may coact with the surfaces c' and c'' of the stone-carrier c . Between the surfaces 11 and 12 the body 10 is longitudinally channeled as at 13 to a depth greater than the maximum protrusion of the stone from the stone-carrier, the channel-width being preferably only slightly greater than the width of the stone; and while the width of the surfaces 11 and 12 (and consequently extent of their bearing-contact on the stone-carrier) may be varied, it is preferable that their transverse or cross-sectional contours shall correspond quite accurately with the contours of surfaces c' and c'' of the stone-carrier. Also, where the stone is disposed in a holder b which protrudes at its edges somewhat beyond the surfaces c' and/or c'' of the stone-carrier, recesses as shown at 14 and 15 are preferably made in the edge of the dressing-tool body, flanking the stone-receptive channel 13, so that the protruding portions of said holder b may serve as lateral guides, and take the wear, when the dressing-tool body is being reciprocated longitudinally along the stone-carrier.

The depth of the dressing-tool body need not be great throughout the longitudinal end portions thereof, but at the center of its length I preferably provide a rather deep or tall extension 17 which serves both as a convenient handle and as an extension frame to receive the bearing-block to be described.

Although the contour of such handle part may be widely varied, it may best be of such longitudinal extent, depth, and top curvature that it may easily be firmly grasped between the heel of the hand and the finger for forceful manipulation of the tool.

In the preferred form of construction a guide-way 18 is formed in the body as a straight-sided recess opening toward the working face of the body, extending well into the depth of the extension 17, and open also at both side faces of the body and extension. In this guide recess is arranged the adjustable bearing member for the dressing roll, such member 19 taking the form of a block making a neat fit in the guideway, said block having two arms 20 laterally separated to accommodate between them the dressing roll 21 and being also apertured as at 22 to afford bearing for the dressing-roll arbor 23.

The main dressing-element 21 is preferably of substantially greater width than the width of the stone, and presents peripherally a series of points or teeth adapted to clean and sharpen the stone with a crushing action. Specifically I prefer that the element be made up of a series of toothed laminæ or relatively thin rings 21^a, arranged side by side substantially to fill the space between the arms 20—20 of the bearing block 19, but each free to rotate upon the arbor 23, so

that the crushing-tooth pattern changes during operation as the individual discs may rotate slightly differently, and so that undue wear upon, or breakage of, one or more discs may readily be compensated for by replacement at least expense.

The bearing block 19 is adjustable vertically and laterally, and also angularly, in the open-sided guide-way 18 through an adequately large range of movements, but may firmly be held in any adjusted position. To these ends set screws 26 and 27, adjustable through the top of the extension 17, bear upon the top of the block 19 near opposite side edges thereof, while set screw 28 working through one end face of the extension 17 engages in a recess 29 in the proximate face of the bearing block 19 and clamps the block against lateral displacement. When set screw 28 is loosened the block may be angularly turned or vertically or laterally moved through quite a range of displacements, but the recess 29 being closed at its top, the block may not fall out. As indicated in Fig. 3 by the solid line and dotted line positions of the bearing block 19 a corner of the stone or the entire surface of the stone may be dressed to various angular positions. Each of the set screws shown has its outer end socketed for reception of a suitable socket wrench.

Operation of the stone dressing-tool requires no particular training or skill. To merely clean and sharpen the stones of a grinding tool, the bearing block 19 is adjusted so that when the dressing roller bears upon the surface a' of the stone the guide-surfaces 11 and 12 of the tool are slightly spaced away from the surfaces c' and c'' of the stone carrier. Under quite heavy manual pressure the tool is run backward and forward, crushing the surface a' of the stone into sharpness and cleanliness, until both surfaces 11 and 12 of the tool are sliding upon the corresponding metal surfaces of the carrier for the stone, substantial side play being prevented by the guidance of the tool-recesses 14 and 15 upon the sides of the stone-holder b . For dressing a tapered stone (i. e., higher at one end than at the other) to remove the taper, the dressing roller is adjusted for a mere cleaning operation at the low end of the stone and will be worked until the high end is worn down. For dressing the stone to a new angle of presentation, angular adjustment of the roller may be had as suggested in Fig. 3. It will be observed that by the provision of a long body, having substantially full length bearing on the stone-carrier as long as the dressing roller is in the contact with any portion of the stone, and making the body of considerable width and with ample bearing surfaces for coaction with the stone-carrier on opposite sides

of the stone, it is substantially insured that when the work is finished to the point where the stone-carrier and tool-body make sliding engagement with their metal surfaces fully 5 in contact, the stone will show uniform dressing of all portions that have been within reach of the dressing roller.

For some characters of stone it is desirable that the dressing be more or less done 10 by a scraping form of tool rather than a crushing form, and as shown in Figs. 8 and 9, a deep recess 31 may be formed in the working edge of the tool body opening to that edge and to the side faces of the body, 15 and extending diagonally from side face to side face, as best shown in Fig. 9, preferably at an angle of 45 degrees to the longitudinal line of the channel 13. In this channel is disposed a scraping blade 32 toothed 20 at its working surface, and preferably made of laminæ, each serrated at its working edge, the "pack" of blades substantially filling the channel 31 and clamped laterally therein by set screws 33 and 34 entering from opposite 25 side faces of the body, the vertical position of the pack within the recess 33 being determined by adjustment of the set screws 36 and 37 entering the recess through the top or back of the body. Manifestly, 30 with such construction either the roll or the blades may be used alone, by adjustment of the other to non-functioning position or by removal or omission of the other.

While I have herein described in some 35 detail particular embodiments of my invention for purposes of full disclosure it will be understood by those skilled in the art that numerous changes in detail of construction and arrangement of parts may be made 40 without departure from the spirit of my invention, within the scope of the appended claims.

I claim:

1. A stone-dressing tool comprising, in 45 combination, a body-member having a stone-receptive channel in one edge and guiding surfaces flanking said channel and adapted to coact with and be guided by the stone-carrier, a stone-dressing element extending 50 across the width of said channel and adjustable in the direction of depth of said channel to vary its effective distance from said guide surfaces, and adjusting means for determining the adjusted position of said dressing element.

2. In a tool for dressing the abrasive 55 stones of cylinder grinders, a body member having longitudinally extensive guide surfaces at one edge thereof for sliding coaction with the abrasive-stone carrier and having a stone-receptive recess in said edge; a stone-dressing element crossing said channel adjacent the longitudinal center of the body and adjustable to vary its distance 60 from the guiding surfaces of the body, and

means for fixing said dressing element in different adjusted positions.

3. In a hand-tool for dressing the abrasive stones of cylinder-grinders and the like, the combination of a body adapted for guiding cooperation with the stone-carrier and having at one edge a stone-receptive channel flanked by longitudinally extensive, guiding edge-surfaces; a stone-dressing element extending across said channel at the longitudinal mid-portion of the body and adjustable to vary its distance from and its angular relation to said guiding edge-surfaces, and means for fixedly holding said element in any said position of adjustment. 70 75 80

4. A structure as set forth in claim 3 wherein said body is provided with a cross-slot to receive said dressing-element and said adjustment-determining means comprise set screw elements entering said slot from the back of the body and adjacent the side-surfaces thereof to receive the working thrust of said dressing element and retaining-screw means entering said slot through a side wall thereof. 90

5. In a hand-tool for dressing the abrasive stones of cylinder grinders and the like, the combination of a body-member having in its working edge a stone-receptive channel flanked by longitudinally extensive 65 guide-surfaces adapted to coact with surfaces of the stone-carrier, a lateral extension from said body adjacent the middle of its length, shaped for hand grip; said body having a transverse recess crossing said stone-receptive channel and entering said extension; a bearing-member movably arranged in said recess; a cylindrical, toothed dressing roller mounted in said bearing member to extend into and across 105 said stone-receptive channel, and adjustable means for positioning said bearing member at different distances back from the guiding edge-surfaces of the body. 110

6. In a hand-tool for dressing the abrasive stones of cylinder grinders and the like, the combination of a body-member having in its working edge a stone-receptive channel flanked by longitudinally extensive 115 guide-surfaces adapted to coact with surfaces of the stone-carrier, a lateral extension from said body adjacent the middle of its length, shaped for hand grip; said body having a transverse recess crossing said stone-receptive channel and entering said extension; a bearing-member movably arranged in said recess; a cylindrical, toothed dressing roller mounted in said bearing member to extend into and across said stone-receptive channel, adjustable means 120 for positioning said bearing member at different distances back from the guiding edge-surfaces of the body, and with the dressing roller in different angular positions with respect to said guiding surfaces. 125 130

7. In a hand-tool for dressing the abrasive stones of cylinder grinders and the like, the combination of a body-member having in its working edge a stone-receptive channel flanked by longitudinally extensive guide-surfaces adapted to coact with surfaces of the stone-carrier, a lateral extension from said body adjacent the middle of its length, shaped for hand grip; said body 10 having a transverse recess crossing said stone-receptive channel and entering said extension; a bearing-member movably arranged in said recess; a cylindrical, toothed dressing roller mounted in said bearing member to extend into and across said stone-receptive channel, adjustable means for positioning said bearing member at different distances back from the guiding edge-surfaces of the body, and with the dressing 15 roller in different angular positions with respect to said guiding surfaces, said adjusting means comprising two set screws bearing on the back of the bearing-member adjacent the side surfaces thereof.
- 20 8. In a dressing-tool for the abrasive stones of cylinder grinders and the like, a body member having a stone-receptive channel in one edge, flanked by edge guide-surfaces adapted for coaction with the stone-carrier, and a stone-dressing element arranged transversely of said channel and presenting its working portion within the depth of said channel, said dressing element comprising a crushing-cylinder having peripheral teeth and rotatable as the tool is moved along the stone.
- 25 9. In a dressing-tool for the abrasive stones of cylinder grinders and the like, a body member having a stone-receptive channel in one edge, flanked by edge guide-surfaces adapted for coaction with the stone-carrier, and a stone-dressing element arranged transversely of said channel and presenting its working portion within the 30 depth of said channel, said dressing element comprising a crushing-cylinder having peripheral teeth and rotatable as the tool is moved along the stone.
- 35 10. In a hand-tool for dressing the abrading stones of cylinder grinders and the like, the combination of a body member having in one edge a stone-receptive channel and at such edge providing longitudinally-extensive guide-surfaces flanking said channel, said body having adjacent its mid-portion a recess crossing said channel; a bearing member arranged in said recess and movable therein to vary its angular relation to and its distance from said guide-surfaces, means for positioning said bearing member fixedly in said body in any adjusted relation aforesaid; and a stone-crushing dressing-roll carried by said bearing member and presenting the working portion of its periphery transversely to and within the depth of said channel.
- 40 11. In a hand-tool for dressing the abrading stones of cylinder grinders and the like, the combination of a body member having in one edge a stone-receptive channel and at such edge providing longitudinally-extensive guide-surfaces flanking said channel, said body having adjacent its mid-portion a recess crossing said channel; a bearing member arranged in said recess and movable therein to vary its angular relation to and its distance from said guide-surfaces, means for positioning said bearing member fixedly in said body in any adjusted relation aforesaid; and a stone-crushing dressing-roll carried by said bearing member and presenting the working portion of its periphery transversely to and within the 45 depth of said channel, said roll member comprising an arbor mounted in said bearing member and a plurality of toothed rings arranged side by side and independently rotatable upon said arbor.

50 peripheral teeth and rotatable as the tool is moved along the stone, said cylinder comprising a plurality of toothed discs rotatable independently of each other.

55 10. In a hand-tool for dressing the abrading stones of cylinder grinders and the like, the combination of a body member having in one edge a stone-receptive channel and at such edge providing longitudinally-extensive guide-surfaces flanking said channel, said body having adjacent its mid-portion a recess crossing said channel; a bearing member arranged in said recess and movable therein to vary its angular relation to and its distance from said guide-surfaces, means for positioning said bearing member fixedly in said body in any adjusted relation aforesaid; and a stone-crushing dressing-roll carried by said bearing member and presenting the working portion of its periphery transversely to and within the depth of said channel.

60 11. In a hand-tool for dressing the abrading stones of cylinder grinders and the like, the combination of a body member having in one edge a stone-receptive channel and at such edge providing longitudinally-extensive guide-surfaces flanking said channel, said body having adjacent its mid-portion a recess crossing said channel; a bearing member arranged in said recess and movable therein to vary its angular relation to and its distance from said guide-surfaces, means for positioning said bearing member fixedly in said body in any adjusted relation aforesaid; and a stone-crushing dressing-roll carried by said bearing member and presenting the working portion of its periphery transversely to and within the depth of said channel.

65 11. In a hand-tool for dressing the abrading stones of cylinder grinders and the like, the combination of a body member having in one edge a stone-receptive channel and at such edge providing longitudinally-extensive guide-surfaces flanking said channel, said body having adjacent its mid-portion a recess crossing said channel; a bearing member arranged in said recess and movable therein to vary its angular relation to and its distance from said guide-surfaces, means for positioning said bearing member fixedly in said body in any adjusted relation aforesaid; and a stone-crushing dressing-roll carried by said bearing member and presenting the working portion of its periphery transversely to and within the depth of said channel.

70 11. In a hand-tool for dressing the abrading stones of cylinder grinders and the like, the combination of a body member having in one edge a stone-receptive channel and at such edge providing longitudinally-extensive guide-surfaces flanking said channel, said body having adjacent its mid-portion a recess crossing said channel; a bearing member arranged in said recess and movable therein to vary its angular relation to and its distance from said guide-surfaces, means for positioning said bearing member fixedly in said body in any adjusted relation aforesaid; and a stone-crushing dressing-roll carried by said bearing member and presenting the working portion of its periphery transversely to and within the depth of said channel.

75 11. In a hand-tool for dressing the abrading stones of cylinder grinders and the like, the combination of a body member having in one edge a stone-receptive channel and at such edge providing longitudinally-extensive guide-surfaces flanking said channel, said body having adjacent its mid-portion a recess crossing said channel; a bearing member arranged in said recess and movable therein to vary its angular relation to and its distance from said guide-surfaces, means for positioning said bearing member fixedly in said body in any adjusted relation aforesaid; and a stone-crushing dressing-roll carried by said bearing member and presenting the working portion of its periphery transversely to and within the depth of said channel.

80 11. In a hand-tool for dressing the abrading stones of cylinder grinders and the like, the combination of a body member having in one edge a stone-receptive channel and at such edge providing longitudinally-extensive guide-surfaces flanking said channel, said body having adjacent its mid-portion a recess crossing said channel; a bearing member arranged in said recess and movable therein to vary its angular relation to and its distance from said guide-surfaces, means for positioning said bearing member fixedly in said body in any adjusted relation aforesaid; and a stone-crushing dressing-roll carried by said bearing member and presenting the working portion of its periphery transversely to and within the depth of said channel.

85 11. In a hand-tool for dressing the abrading stones of cylinder grinders and the like, the combination of a body member having in one edge a stone-receptive channel and at such edge providing longitudinally-extensive guide-surfaces flanking said channel, said body having adjacent its mid-portion a recess crossing said channel; a bearing member arranged in said recess and movable therein to vary its angular relation to and its distance from said guide-surfaces, means for positioning said bearing member fixedly in said body in any adjusted relation aforesaid; and a stone-crushing dressing-roll carried by said bearing member and presenting the working portion of its periphery transversely to and within the depth of said channel.

90 11. In a hand-tool for dressing the abrading stones of cylinder grinders and the like, the combination of a body member having in one edge a stone-receptive channel and at such edge providing longitudinally-extensive guide-surfaces flanking said channel, said body having adjacent its mid-portion a recess crossing said channel; a bearing member arranged in said recess and movable therein to vary its angular relation to and its distance from said guide-surfaces, means for positioning said bearing member fixedly in said body in any adjusted relation aforesaid; and a stone-crushing dressing-roll carried by said bearing member and presenting the working portion of its periphery transversely to and within the depth of said channel.

HORACE C. HEON.
